UNITED STATES PATENT OFFICE.

WILLIAM F. FRIEDMAN, OF WASHINGTON, DISTRICT OF COLUMBIA.

SECRET-SIGNALING APPARATUS FOR AUTOMATICALLY ENCIPHERING AND DECIPHERING MESSAGES.

Application filed April 14, 1922. Serial No. 552,578.

To all whom it may concern:

Be it known that WILLIAM F. FRIEDMAN, citizen of the United States, residing at Washington, D. C., has invented certain new and useful Improvements in Secret-Signaling Apparatus for Automatically Enciphering and Deciphering Messages, of which the following is a specification.

This invention relates to improvements in secret signaling systems, more particularly to electrical apparatus for the automatic encipherment, transmission, reception and decipherment of messages, and has for its object the provision of apparatus of such arrangement as will insure a higher degree of secrecy than is the case in the heretofore prevalent apparatus. The invention is here illustrated as applied to a well-known form of printing telegraph systems but is applicable to other signaling systems, as will readily be understood.

As constituted at present printing telegraph machines adapted for the automatic encipherment and decipherment of messages employ but one arrangement or combination of connections for establishing the necessary electrical circuits concerned directly in the encipherment and decipherment of messages, a condition which greatly facilitates decipherment of the messages by unauthorized persons. Such unauthorized decipherment is very greatly complicated and rendered almost impossible if the arrangements or combinations of connections in the various enciphering and deciphering circuits are made susceptible of variation at the will of the correspondents, a condition accomplished through the instrumentalities of my invention.

In order that the invention and its mode of application may be readily understood by persons skilled in the art, I have, in the accompanying illustrative drawings, and in the detailed following description based thereon, set forth several embodiments of the same.

In these drawings Figure 1 is a diagrammatic view of the circuits concerned directly in the enciphering and deciphering operations as constituted in the heretofore prevalent apparatus.

Figure 2 is a diagrammatic view of one form of modified circuits whereby a total of one hundred and twenty different sets of electrical circuits for enciphering and deciphering messages are made possible, any one of which may be selected and agreed upon for use at the will of the correspondents.

Figures 3, 4, 5, 6, and 7 are diagrammatic views of other forms of modified circuits whereby a similar number of different sets of combinations of circuits may be obtained as in Figure 2.

Figure 8 is a diagrammatic view of a modified form of circuits concerned in the transmission and reception of signals, whereby a total of one hundred and twenty different sets of electrical circuits for transmitting and receiving the signals are made possible, any one of which may be selected for use at the will of the operator.

In these drawings, only such parts of the apparatus as are necessary to an understanding of my invention are illustrated, all other parts required in the proper operation of the apparatus being well known. Furthermore, in order that my invention be understood, it is necessary to give a brief description of the mechanics of the encipherment and decipherment operations in the heretofore existent apparatus.

Having more particular reference to the drawings, in connection with which like characters of reference will designate corresponding parts thereof, A, B, and C are transmitters of a form well known in printing telegraph apparatus, controlled by perforated tapes containing perforations disposed transversely across the tape in such combinations as to allow each letter of the alphabet and certain functions of a printing mechanism to be represented by a particular combination of perforations known as code signals. Thus, the letter "A", for example, is represented by perforations in the first and second positions across the tape, and the code signal for that letter may be represented by "+ + - - -", where "+" represents a positive current impulse, and "-" represents a negative current impulse, although it is to be understood that an "open and closed" circuit method of opera-

tion may be used instead of positive and negative current impulses, in which case "+" represents a "closed" or "marking" impulse and "—" represents an "open" or "spacing" impulse. The letter "B" is represented by perforations in the first, fourth and fifth positions across the tape, and the code signals therefor are "+ — — + +", and so on. Each transmitter is provided with a set of five movable contacts which vibrate between and make contact with two bus-bars which are connected to the positive and negative poles of a battery, or to battery and ground in the case of the "open" and "closed" circuit method of operation. In transmitter A the two bus-bars are designated as A^{21} and A^{22} , positive and negative, respectively; the vibrating contacts are designated as A^1 , A^2 , A^3 , A^4 and A^5 . In transmitters B and C the corresponding bus-bars are designated as B^{21} and B^{22} , C^{21} and C^{22} , respectively; the sets of vibrating contacts are designated as B^1 to B^5 and C^1 to C^5 , respectively. Transmitters A and B will be designated also as the "key-tape transmitters" because they are controlled by two tapes which constitute the "key" for the encipherment and decipherment of the messages; transmitter C will be designated also as the "message transmitter" because it is controlled by a tape bearing the plain text message in the case of encipherment, or the cipher message, in the case of decipherment.

Transmitters A and B jointly control the operation of relays 1, 2, 3, 4, and 5, which are known form, and which will hereafter be designated as the "key relays" since they are controlled by the key-tape transmitters A and B. Relays 6, 7, 8, 9 and 10, of known form and designated hereafter as the "cipher relays", are controlled by the joint operation of contacts C^1 to C^5 and the armatures 23 to 27 of relays 1 to 5. Numerals 11, 12, 13, 14 and 15 are the magnets of an automatic tape perforator, designated hereafter as the "machine perforator". These magnets control the operation of punches which perforate the tape produced for the cipher message, and will be designated hereafter as the "punch magnets". They are actuated by circuits established through the energizing of cipher relays 6, 7, 8, 9 and 10. Numerals 16, 17, 18, 19 and 20 are the magnets of the printing mechanism which types the letters on a sheet or roll of paper. These magnets perform the function of selecting the specific character to be printed and will be designated hereafter as the "selecting magnets". They are also actuated by circuits established through the operation of cipher relays 6, 7, 8, 9 and 10.

Referring now to transmitter A, Figure 1, bar A^{21} is connected to the positive pole of battery 39, bar A^{22} is connected to the

negative pole of battery 39. Each of the 61 vibrating contacts A^1 , A^2 , A^3 , A^4 and A^5 can touch either A^{21} or A^{22} and thus determine the polarity of current transmitted to the lines leading to the relays 1, 2, 3, 4, and 5. Which of the two bars A^{21} or A^{22} any of 70 these vibrating contacts touches is determined by the perforations in the tape; if there is a perforation in position 1 in the tape, then contact A^1 touches bar A^{21} ; if there is no perforation in position 1 of the tape, 75 then contact A^1 touches bar A^{22} . The same applies to contacts A^2 , A^3 , A^4 and A^5 , which are governed by the presence or absence of perforations in positions 2, 3, 4 and 5, respectively across the tape. What has been 80 said of the operation of transmitter A applies equally to the operation of transmitter B with its corresponding or homologous vibrating contacts B^1 , B^2 , B^3 , B^4 and B^5 which make contact with either bar B^{21} , 85 which is connected to the positive pole of battery, or B^{22} , which is connected to the negative pole of battery. The two sets of contacts A^1 to A^5 and B^1 to B^5 are operated 90 synchronously so that all the contacts touch the bars at exactly the same moment, though of course, some of them touch the bars of positive polarity, the others touch the bars of negative polarity, depending upon the particular combinations of perforations in the respective tapes going through the transmitter at that moment.

It will be noted that the circuits of relays 1, 2, 3, 4 and 5 really constitute five independent circuits. The circuit of relay 100 1, for example, is that in which the pair of corresponding or homologous contacts A^1 and B^1 are the determining members; the circuit of relay 2 is that in which the pair of homologous contacts A^2 and B^2 are the determining members, and so on. Each pair of homologous contacts can therefore affect one and only one of the key relays, viz, that key relay whose operation is controlled by that particular pair of homologous contacts. 105

One of the four following conditions with respect to the operation or non-operation of relay 1 may exist at a given moment:

(1) Contact A^1 may be touching bar A^{21} 110 when contact B^1 is touching bar B^{22} . An electrical circuit is thereby established from positive pole of battery 39, through A^{21} , A^1 , winding of relay 1, B^1 , B^{22} , to negative pole of battery 39. Relay 1 is therefore energized.

(2) Contact A^1 may be touching bar A^{22} 115 when contact B^1 is touching bar B^{21} . An electrical circuit is thereby established from positive pole of battery 39 through B^{21} , B^1 , winding of relay 1, A^1 , A^{22} , to negative pole of battery 39. Relay 1 is therefore energized.

(3) Contact A^1 may be touching bar A^{21}

when contact B^1 is also touching bar B^{21} . No circuit is established for both A^1 and B^1 are touching bars which are of positive polarity, no difference in potential exists and 5 relay 1 is therefore not energized.

(4) Contact A^1 may be touching bar A^{22} when contact B^1 is also touching bar B^{22} . No circuit is established for both A^1 and B^1 are touching bars which are of negative 10 polarity, no difference in potential exists and relay 1 is therefore not energized.

It is obvious therefore that relay 1 can be operated only when the two homologous contacts A^1 and B^1 are touching bars of opposite polarity. If contact A^1 is touching the bar of positive polarity, then contact B^1 must be touching the bar of negative polarity in order to energize relay 1, and vice versa.

20 What has been said of contacts A^1 and B^1 and of relay 1 applies equally to the other homologous pairs of contacts A^2 and B^2 , A^3 and B^3 , A^4 and B^4 , A^5 and B^5 , and their respective relays, 2, 3, 4, and 5. Furthermore, as has already been stated, as the circuits are arranged in the heretofore prevalent apparatus, relays 1, 2, 3, 4, and 5 are absolutely independent of each other, and 25 are energized or unenergized depending only upon the polarity of the terminals of the windings of each relay as controlled by each homologous pair of contacts A^1 and B^1 , A^2 and B^2 , A^3 and B^3 , A^4 and B^4 , A^5 and B^5 , respectively.

30 Transmitter C in Figure 1 functions in exactly the same manner as do transmitters A and B and in synchronism with them; a perforated tape passing through transmitter C determines which of the two bars C^{21} and C^{22} , connected to positive and negative poles, respectively, of battery 40, are touched by its vibrating contacts C^1 , C^2 , C^3 , C^4 and C^5 for each character. These contacts operate synchronously with the contacts in transmitters A and B.

40 The conductors, 60, leading from contacts C^1 , C^2 , C^3 , C^4 , and C^5 form one set of terminals of the windings of cipher relays 6, 7, 8, 9 and 10, respectively. The armatures of key relays 1, 2, 3, 4, and 5 form the other set of terminals of the windings of cipher relays 6, 7, 8, 9, and 10.

45 One of the four following conditions with respect to the operation or non-operation of cipher relay 6 may exist at a given moment:

(1) Contact C^1 may be touching bar C^{21} when relay 1 is unenergized. The normal or unattracted position of the armature of relay 1 is such as to make contact with negative pole of battery 40. Therefore the circuit for energizing relay 6 is completed, for a current starts flowing from positive pole 50 of battery 40, through bar C^{21} , contact C^1 , winding of relay 6, armature of relay 1 to

negative pole of battery 40, and relay 6 is therefore energized.

(2) Contact C^1 may be touching bar C^{21} when relay 1 is energized. The position of armature 23 of relay 1 when relay 1 is energized is such as to make contact with positive pole of battery 40. Therefore the circuit for energizing relay 6 is not completed, for both terminals of the winding of this relay are then connected with the positive 70 pole of battery 40, and relay 6 therefore remains unenergized.

(3) Contact C^1 may be touching bar C^{22} when relay 1 is unenergized. The circuit for energizing relay 6 is not completed, for 80 both terminals of the winding of this relay are then connected with the negative pole of battery 40, and relay 6 therefore remains unenergized.

(4) Contact C^1 may be touching bar C^{22} when relay 1 is energized. The circuit for energizing relay 6 is therefore completed, for a current starts flowing from positive pole of battery 40, through armature 23 of relay 1, winding of relay 6, contact C^1 , bar C^{22} , to negative pole of battery 40, and relay 6 is therefore energized.

It is obvious therefore that relay 6 can be energized only when conditions (1) and 95 (4) above obtain, that is, when the terminals of the winding of this relay are connected to both polarities of the battery. What has been said of cipher relay 6 applies also to cipher relays 7, 8, 9 and 10, controlled by armatures 24, 25, 26, and 27 and contacts C^2 , C^3 , C^4 and C^5 .

100 It is likewise apparent here that as the circuits are arranged in the heretofore prevalent apparatus, as shown in Figure 1, cipher relays 6, 7, 8, 9 and 10 are absolutely independent of each other, and are energized or unenergized depending only upon the polarity of the terminals of the winding of each relay as controlled by each homologous pair of contacts C^1 and armature 23, C^2 and armature 24, C^3 and armature 25, C^4 and armature 26, C^5 and armature 27, these armatures being of course controlled by the operation of the five independent key relays.

110 When cipher relay 6 is energized, the armatures 28 and 29 are attracted and thus make contact with positive pole of battery 70; a current flows from positive pole of battery 70 through armatures 28 and 29, the windings of magnets 11 and 16, and, if keys 66 and 67 are closed, to the negative pole of battery 70, thus completing the circuit and operating punch magnet 11 and selecting magnet 16. What has been said of the operation of cipher relay 6 and magnets 11 and 16 applies also to the operation of cipher relays 7, 8, 9 and 10, punch magnets 12, 13, 14, 15, and selecting magnets 17, 18, 19 and 20.

Punch magnets 11 to 15 determine the location of the perforations to be made in a cipher tape by the automatic or machine perforator, and selecting magnets 16 to 20 5 determine the operations executed by the printer in selecting the characters to be printed and performing the necessary functions of feeding the paper roll, shifting the carriage, etc.

10 Since the operation or non-operation of key relays 1 to 5 is directly determined by the positions of the vibrating contacts in transmitters A and B, and since the operation or non-operation of cipher relays 6 to 15 10 is determined by the operation or non-operation of key relays 1 to 5 in conjunction with the positions of the contacts in transmitter C; and since the operation of magnets 11 to 20 is determined by the operation 20 of cipher relays 6 to 10, it is clear that the cipher tape perforated, or the characters printed by the printer, are thus the resultants of the interaction of all the electrical circuits controlled jointly by all three transmitters A, B, and C, through the intermediary of the relays 1 to 10 controlled by these transmitters.

Let us suppose that at a given moment the character "X," normal code signal 30 "+ - + + +" represented by perforations at positions 1, 3, 4, and 5 across the tape is passing through transmitter A, and character "Y" normal code signal "+ - + - +", represented by perforations at positions 1, 3 35 and 5 across a second tape, is passing through transmitter B. Contact A¹ will touch bar A²¹, and contact B¹ will touch bar B²¹; both contacts will therefore be touching bars of positive polarity; no circuit is 40 established and therefore relay 1 is not energized. Contacts A² and B² will both be touching bars of negative polarity; no circuit is established and therefore relay 2 is not energized. Contacts A³ and B³ will 45 both be touching bars of positive polarity; no circuit is established and hence relay 3 is not energized. Contact A⁴ will be touching bar A²¹, of positive polarity, contact B⁴ will be touching bar B²² of negative polarity; a 50 circuit is completed and relay 4 is therefore energized. Contacts A⁵ and B⁵ will both be touching bars of positive polarity; no circuit is completed and therefore relay 5 is not energized. The direct resultant of the 55 interaction of characters "X" and "Y" when simultaneously passing through transmitters A and B, is that only relay 4 is energized, relays 1, 2, 3, and 5 remaining unenergized. Armatures 23, 24, 25 and 27 will therefore 60 be making contact to negative pole of battery 40, armature 26 to positive pole of battery 40. If now, at the same instant character "Z," normal code signal "+ - - +", represented by perforations in positions 1 65 and 5 across a third tape is passing through

transmitter C, then we will have the following:

(1) Contact C¹ is against bar C²¹, which is connected to positive pole of battery 40, armature 23 is connected to negative pole of battery 40. Relay 6 is therefore energized. 70

(2) Contact C² is against bar C²², which is connected to negative pole of battery 40, armature 24 is connected to negative pole of battery 40. Relay 7 is therefore not energized. 75

(3) Contact C³ is against bar C²², which is connected to negative pole of battery 40, armature 25 is connected to negative pole of battery 40. Relay 8 is therefore not energized. 80

(4) Contact C⁴ is against bar C²², which is connected to negative pole of battery 40, armature 26 is connected to positive pole of battery 40. Relay 9 is therefore energized. 85

(5) Contact C⁵ is against bar C²¹, which is connected to positive pole of battery 40, armature 27, is connected to negative pole of battery 40. Relay 10 is therefore energized. 90

If key 66 is closed, key 67 open, magnets 11, 14, and 15 will be operated, perforating holes in positions 1, 4 and 5 across the cipher tape which will represent the letter "B", the normal code signal for which is "+ - - + +." The cipher resultant of the interaction of letters "X", "Y", and "Z", will therefore be the letter "B." If key 67 is closed, magnets 16, 19 and 20 will be operated and this will result in the selection of the letter "B" for printing by the printing mechanism. 95

As soon as the resultant of one set of characters passing through the two key-tape transmitters and the message transmitter has been perforated, a new set of 105 characters is presented at the three transmitters and another character is perforated by the machine perforator, and so on until a cipher tape is produced which represents the resultants of the electrical combination 110 of two-tapes and the message tape. This cipher tape is then transmitted over the line in the usual manner and at the receiving end a duplicate of the cipher tape transmitted is perforated in a well-known manner by an automatic perforator. The duplicate cipher tape thus prepared is then run through message transmitter C together with key tapes which are duplicates 115 of those at the transmitting end and which are run through key-tape transmitters A and B. This effects the decipherment of the message and it may be perforated by the machine perforator or printed by the printer. To illustrate the steps in the 120 decipherment, let us follow through the decipherment of the letter "B" whose decipherment I have just demonstrated. Letters "X" and "Y" will be presented at key-tape transmitters A and B, and the 125 130

result upon key relays 1 to 5 will of course be exactly the same as before, relay 4 being the only one energized, and armatures 23, 24, 25 and 27 making contact to negative pole of battery 40, armature 26, to positive pole of battery 40. If now the character "B" represented as we have seen, by perforations in positions 1, 4, and 5 across the tape, is passing through transmitter C, then we will have following:

(1) Contact C^1 is against bar C^{21} , which is connected to positive pole of battery 40, armature 23 is connected to negative pole of battery 40. Relay 6 is therefore energized.

(2) Contact C^2 is against bar C^{22} , which is connected to negative pole of battery 40, armature 24 is also connected to negative pole of battery 40. Relay 7 is therefore not energized.

(3) Contact C^3 is against bar C^{22} , which is connected to negative pole of battery 40, armature 25 is also connected to negative pole of battery 40. Relay 8 is therefore not energized.

(4) Contact C^4 is against bar C^{21} , which is connected to positive pole of battery 40. Armature 26 is also connected to positive pole of battery 40. Relay 9 is therefore not energized.

(5) Contact C^5 is against bar C^{21} , which is connected to positive pole of battery 40, armature 27 is connected to negative pole of battery 40. Relay 10 therefore is energized.

If keys 66 and 67 are closed magnets 11, 15, 16 and 20 will be operated, and the character perforated and printed is "+ - - +" which is "Z." Thus, cipher character "B" has been correctly deciphered by key characters "X" and "Y" into plain-text character "Z."

Now it is clear that in encipherment the printing of the letter "B", or the perforation of a cipher tape with perforations representing the letter "B" as the resultant of the interaction of letters "X", "Y", and "Z" in transmitters A, B and C, respectively, and in decipherment the perforation of a plain-text tape with perforations representing the letter "Z", or the printing of the letter "Z" as the resultant of the interaction of letters "X", "Y", and "B" in transmitters A, B, and C, respectively, is dependent upon the arrangement of the circuits shown in Figure 1. The machines as at present constituted employ but one set or combination of enciphering circuits, and permit of no changes in the connections between the various contact points, relays and magnets concerned directly in the enciphering operations. The interaction of letters "X", "Y" and "Z" will always yield "B" as the cipher resultant; the interaction of letters "X",

"Y" and "B" will always yield "Z" as the deciphered character. The same holds true with respect to the various resultants of all other combinations of letters: these resultants in the apparatus as constituted heretofore, are always constant in nature, dependent only upon the letters which enter into the reaction.

The principal feature of Figure 1 to which attention is directed in connection with the essential nature of my invention is that final operation of magnets 11 to 20 is determined by the positions of three sets of five homologous contacts in all three transmitters A, B, and C, as controlling relays corresponding to homologous pairs of contacts. Magnets 11 and 16, for example, are operated by a circuit controlled by cipher relay 6, the operation of which is in turn controlled by the positions of the three homologous contacts A^1 , B^1 and C^1 .

Figure 2 shows a switching or connection-changing device E, inserted in the conductors 61, connecting contacts A^1 , A^2 , A^3 , A^4 and A^5 to the windings of the five relays 1, 2, 3, 4, and 5. This device E may be any one of a number of forms of switchboards or connection-changing devices, preferably one of the telephone switchboard type, with plugs and jacks, but any other form of connection-changing apparatus may be used. By means of this switchboard it now becomes possible to connect the set of five contacts A^1 , A^2 , A^3 , A^4 and A^5 with the windings of the five relays 1, 2, 3, 4, and 5 in 120 different ways or permutations, instead of one and only one arrangement of connections, as is the case in the heretofore prevalent apparatus. In Figure 2 the particular permutation of connections shown may be designated by the number 35214, indicating that contact A^1 is now in the circuit of relay 3; contact A^2 , in that of relay 5; contact A^3 , in that of relay 2; contact A^4 , in that of relay 1; and contact A^5 , in that of relay 4.

Let us now consider what happens when letters "X", "Y", and "Z" are passing through transmitters A, B, and C, respectively. The following is a summary of the reactions which occur in Figure 2:

(1) Contact A^1 is against bar A^{21} , which is connected to positive pole of battery 39. A^1 is connected to jack 41, to plug 46, to jack 53, to winding of relay 3, to contact B^3 , which is then against bar B^{21} , which is connected to positive pole of battery 39. Relay 3 therefore remains unenergized; hence armature 25 remains in its unattracted position, making contact with negative pole of battery 40. Contact C^3 is then against bar C^{22} , which is connected to negative pole of battery 40. Relay 8 therefore remains unenergized; hence armature 32 re-

mains in its unattracted position, making no contact to battery 70. Hence magnet 13 remains inoperative and no perforation is made at position 3 across the tape.

5 (2) Contact A² is against bar A²¹, which is connected to negative pole of battery 39. A² is connected to jack 42, to plug 47, to jack 55, to winding of relay 5, to contact B⁵, which is then against bar B²¹, which is 10 connected to positive pole of battery 39. A circuit is completed through the winding of relay 5 and it is therefore energized; hence armature 27 is attracted, making contact with positive pole of battery 40. Contact C⁵ is then against bar C²¹, which is also 15 connected with positive pole of battery 40. No circuit is completed through relay 10 and it therefore remains unenergized; hence armature 36 remains in its unattracted position, making no contact to battery 70. Hence magnet 15 remains inoperative and no perforation is made at position 5 across the tape.

20 (3) Contact A³ is against bar A²¹, which is connected to positive pole of battery 39. A³ is connected to jack 43, to plug 48, to jack 52, to winding of relay 2, to contact B², which is then against bar B²², which is connected to negative pole of battery 39. A 25 circuit is completed through the winding of relay 2, and it is therefore energized; hence armature 24 is attracted, making contact with positive pole of battery 40. Contact C² is then against bar C²², which is connected to negative pole of battery 40. A circuit is completed through the winding of 30 relay 7, and it is therefore energized; hence armature 30 is attracted, making contact to positive pole of battery 70, and a current flows from positive terminal of battery 70 through armature 30, winding of magnet 12 to negative pole of battery 70. Magnet 12 is therefore operated and a 35 perforation is made in position 2 across the tape.

40 (4) Contact A⁴ is against bar A²¹, which is connected to positive pole of battery 39. A⁴ is connected to jack 44, plug 49, jack 51, winding of relay 1, contact B¹, which 45 is then against bar B²¹, which is connected to positive pole of battery 39. No circuit is completed and relay 1 remains therefore unenergized; hence armature 23 remains in its unattracted position, making contact with negative pole of battery 40. Contact C¹ is then against bar C²¹, which is connected to positive pole of battery 40. A circuit is therefore completed through the winding of relay 6 and it is therefore 50 energized; hence armature 28 is attracted, making contact with positive pole of battery 70 and a current flows from positive pole of battery 70 through armature 28, winding of magnet 11 to negative pole of battery 70.

Magnet 11 is operated and a perforation is 65 made in position 1 across the tape.

(5) Contact A⁵ is against bar A²¹, which is connected to positive pole of battery 39. A⁵ is connected to jack 45, to plug 50, to jack 54, to winding of relay 4, to contact 70 B⁴, which is then against bar B²², which is connected to negative pole of battery 39. A circuit is therefore completed through the winding of relay 4, and it is therefore energized; hence armature 26 is attracted, 75 making contact with positive pole of battery 40. Contact C⁴ is then against bar C²², which is connected to negative pole of battery 40. A circuit is therefore completed through the winding of relay 9 and it is 80 therefore energized; hence armature 34 is attracted, making contact to positive pole of battery 70, and a current flows from positive pole of battery 70 through armature 34, winding of magnet 14 to negative pole of 85 battery 70. Magnet 14 is operated and a perforation is made in position 4 across the tape.

The summary or final result is that perforations are made in positions 1, 2, and 4 90 across the tape, making the signal "++-+-", and this combination represents the letter "J" in the conventional code.

95 Here we see that the cipher resultant of the interaction of letters "X", "Y", and "Z" is no longer the letter "B" as was the case before, but an altogether different letter, viz, "J". The cipher perforator would perforate the combination representing letter "J" and the printer would select and print 100 the letter "J".

105 What has been said about the interaction of this particular combination of letters applies to all other combinations of letters; the resultants will be different from those produced by the connections shown in Figure 1. The steps in decipherment are properly modified at the deciphering end since a similar switchboard is inserted in the identical position and is set up for the same permutation of connections as at the enciphering end. The decipherment of the letter "J" by means of key letters "X" and "Y" 110 must yield letter "Z".

115 It is obvious of course that this result will be altogether different for a different permutation of connections established through E. As said before, 120 different permutations of connections are possible. It is necessary of course that the correspondents shall have previously agreed upon the particular permutation of connections they 120 will use during a given period.

125 Now it is obvious that the connection-changing device E may be placed in any one of several locations, each giving different results. The basic principle is, however, the same. In Figure 2 the connection chang-

ing device E is shown as inserted between contacts A^1, A^2, A^3, A^4, A^5 and the conductors 61 leading to the windings of the relays 1, 2, 3, 4, and 5. In Figure 3 the connection changing device E is shown as inserted in the conductors 62 leading from contacts B^1, B^2, B^3, B^4 , and B^5 , to the windings of the relays 1, 2, 3, 4, and 5. The cipher resultant of the interaction of the 10 letters "X", "Y" and "Z" is now the code signal "— + — —", as shown in Figure 3 using the same permutation of connections as before, viz, 35214. The following diagram is a brief method of indicating the 15 reactions in this case:

Since there will be no indication in the cipher message as to exactly which one of the 120 possible permutations of connections is in effect at a given time, an enemy who intercepts or comes into possession of a cipher message would not know which one of a series of 120 different sets of resultants apply in the message or messages which he has obtained, thus making the unauthorized decipherment an extremely difficult matter.

In Figure 4 the connection-changing device E is inserted in the conductors 63 leading from armatures 23, 24, 25, 26, 27 to the windings of relays 6, 7, 8, 9 and 10. As in the preceding case, 120 permutations of connections are likewise possible in this case. The cipher resultant of the interaction of letters "X", "Y" and "Z" with the permutation of connections, 35214, as before, is now the letter "T" as shown by the following diagram:

If the connection-changing device E is inserted in the conductors 60 leading from contacts C^1, C^2, C^3, C^4, C^5 to the windings of cipher relays 6, 7, 8, 9 and 10, as shown in Figure 5, a different result will be ob-

tained with the same permutation, 35214, as before. The resultant is "— + — —" as shown below:

In Figure 6, the connection-changing device E is inserted in the conductors 64 leading from armatures 28, 30, 32, 34, 36 to the windings of magnets 11, 12, 13, 14, and 15. As in the preceding case, 120 different permutations of connections are likewise possible in this case.

In Figure 7, the connection-changing device E is inserted in the conductors 65 leading from armatures 29, 31, 33, 35, 37 to the windings of magnets 16, 17, 18, 19 and 20. As in the preceding case, 120 different permutations of connections are likewise possible in this case.

The connection-changing device E is shown as inserted in the conductors leading only to the perforator magnets in Figure 6, and only to the printer magnets in Figure 7, but it is to be understood that if it is desired to print and perforate the same final code signals, similar connection changing devices with identical permutations of connections would have to be inserted simultaneously in both positions shown in Figures 6 and 7, otherwise the two sets of magnets would act differently, thus producing a perforated tape that would not match the printed message. Usually only one copy would be retained at the transmitting station, either the perforated tape copy or the printed copy.

It is obvious of course, that there are only 120 different permutations of connections in the whole system, for the electrical results of a permutation produced by inserting the connection-changing device E in one position can be duplicated by the electrical results of a permutation produced by inserting the connection-changing device E in another location.

Since the operations of the various parts of the whole apparatus are the same for both encipherment and decipherment, the insertion of the connection-changing device at any of the places shown in the diagrams will serve for decipherment as well as encipherment so long as the permutation of connections that is used at both ends during a given period is the same.

The preceding Figures 1 to 7 apply to that

method of operation in which the encipherment and decipherment of messages is accomplished by local sets, the messages transmitted over the line being transmitted in exactly the same manner as though they were ordinary intelligible messages, with the exception that instead of printing the received messages directly on a printer they must be received and perforated on a tape and this 5 tape message is then deciphered by the local set at the receiving end, in a well-known manner. It is possible, however, to encipher and decipher the messages without the intermediacy of local sets at the two ends, by enciphering and transmitting a message coincidentally at the sending end, and receiving and deciphering it coincidentally at the receiving end. To do this, it is necessary, as shown 10 in Fig. 8, to lead conductors 64 to the segments of the transmitting face of a well-known form of distributor for enciphering and transmitting coincidentally, and conductors 60 to the segments of the receiving face of a similar distributor operating synchronously with the sending distributor for receiving and deciphering coincidentally. In 15 Figure 8 which shows the arrangements for this system of operation, the distributors which are of well-known form, are not shown. In this method of operation, when enciphering and transmitting coincidentally, the set of keys 71 in the conductors 64 leading to the segments 1' to 5' of the transmitting face of the distributor are closed, and 20 the set of keys 72 in the conductors 60 leading to the segments 1" to 5" of the receiving face of the distributor are opened. It is not really necessary to have a copy of the 25 transmitted messages prepared at the transmitting station, but if it is desired to retain a perforated tape copy of the transmitted message, switch 66 is closed, thus allowing 30 perforator magnets 11 to 15 to operate; but switch 67 is opened throwing printer magnets 16 to 20 out of operation as there would 35 be no need of having a printed copy of the unchanged signal. This figure shows the connection changing device E as inserted in the conductors leading to the segments of 40 the transmitting face of the distributor, and also to the perforator magnets. Thus, the original code signal "+---++" as set up at relays 6 to 10 is changed to "+-++-" by E and is transmitted and 45 perforated as the latter. Here again a total of 120 permutations of connections between armatures 28, 30, 32, 34, 36 and segments 1' to 5' and magnets 11 to 15 is possible. Figure 50 8 also shows the insertion of the connection changing device E' in the conductors leading from the segments of the receiving face of the distributor, so that the received signals may be translated back into a form 55 to correspond with their original form as set up at relays 6 to 10 at the transmitting end.

In receiving, transmitter C takes no part in the operation, transmitter contacts C¹ to C⁵ being thrown to a neutral position by a lever arm now shown in the drawing. Switch 67 is closed, allowing printer magnets 16 to 70 20 to function. If a perforated received message is desired, switch 66 is closed, but the connections in E are arranged to connect magnet 11 with armature 28, magnet 12 with armature 30, etc., that is, the arrangement is 75 as if no switchboard E were in the circuit at that point. The permutation of connections at E' as shown in Figure 8 is such as to change the signal "+-++-" as it comes off the segments 1' to 5' into the signal "+---++" when it reaches conductors 80 60 leading to relay 6 to 10. Thus, the unmodified signal originally set up at the cipher relays 6 to 10 at the transmitting end, is brought back into the same signal when it reaches the corresponding cipher relays at 85 the receiving end.

Figures 3, 4, 5, 6, 7, and 8 are meant to show only that the connection-changing device E may be inserted in various other places 90 than those shown in Figure 2. In the specified embodiment of my invention herein disclosed, I have illustrated but two key tape transmitters, five key relays and five cipher relays adapted to encipher or decipher messages, but it is obvious that more key transmitters may be provided to affect the operation of the key relays and the cipher relays; and one or more connection-changing 95 devices may be inserted in the circuits concerned in the additional key transmitters.

Manifestly, the arrangements shown throughout are capable of modification, and such modifications as are within the scope 100 of my claims, I consider within the spirit of my invention.

I claim:

1. An electrical enciphering and deciphering system in which the cipher characters are the resultants of the superimposition and combination of a set of electrical conditions governed by the characters of a pair of key tapes upon the set of electrical conditions governed by message characters, comprising a set of key tape transmitter relays controlled by a pair of key tape transmitters through which said key tapes are passed, a set of cipher relays controlled jointly by said key tape transmitter relays and the message transmitter, a sending and receiving distributor, a printer, an automatic tape perforator, means for transposing in a plurality of ways, within each set, any one of a set of conductors involved in establishing the code combinations equivalent to the characters transmitted, for the purpose of changing the characters that would normally be produced by the superimposition of the set of electrical conditions governed by the key tapes 115 upon the message characters,

2. An electrical enciphering and deciphering system, in which the cipher characters are the resultants of the superimposition and combination of a set of electrical conditions governed by the characters of a pair of key tapes upon the electrical conditions governed by the characters of the message, comprising a set of key tape transmitter relays controlled by a pair of key tape transmitters 10 through which said key tapes are passed, each of the key tape transmitters being provided with a set of vibrating contacts, a set of cipher relays controlled jointly by the key

tape transmitter relays and a message transmitter, means for changing, in a plurality 15 of ways, the connections between the windings of the key tape transmitter relays and the set of vibrating contacts of one of the key tape transmitters for the purpose of changing the characters that would normally be produced by the superimposition of a set of electrical conditions governed by the key tapes upon the message characters.

In testimony whereof I affix my signature.

WILLIAM F. FRIEDMAN.
